POLISHING COPPER ROLLERS.

Application filed January 16, 1923, Serial No. 613,061, and in Germany June 2, 1922.

This invention relates to improved means adapted for use in polishing copper rollers, and has for its objects to enable rollers varying considerably in length to be treated in 5 the same machine, to ensure uniform distribution of the wear over the whole working surface of the polishing stone, and to prevent grit or the like from adhering to the face of the latter or to the roller surface under treatment.

In the accompanying drawings, Fig. 1 is a front elevation illustrating a machine constructed according to our invention, whilst Fig. 2 is a corresponding plan. Fig. 3 is an 15 end elevation, taken from the left-hand end in Fig. 2, whilst Fig. 4 is a detail view, drawn partly in section and to a larger scale, illustrating the construction of the stone-carrier hereinafter described. Fig. 5 is a longitudinal vertical section in the plane of the stone-traversing shaft; and Figs. 6 and 7 are transverse vertical sections in the plane of the stone-carrier. In Fig. 8 is illustrated in side elevation an optional addition wherein a 25 partial rotary movement is imparted to the stone.

Apparatus constructed according to our invention comprises two or more base-frames *a* supporting a bed *a*¹, similar in form to that 30 of a lathe and securely bolted to the frames. Toward the rear extremities of the latter are mounted standards *b*, *b*, adapted to support the polishing stone *c*, its carrier *c*¹, guide-bars *d*, *d*, and mechanism for traversing the stone-carrier along the latter. The brackets *b*, *b*, are united by an overhead tie-plate *b*¹, carrying a pair of spindles *e*, *e*, whereon are freely mounted pulleys *e*¹, *e*¹, carrying the rope of a counter-weight *f*. (See Fig. 3.) Guide-bars *d*, *d* are connected at their extremities to the standards *b*, *b*, and on these guide-bars is mounted a frame *d*¹, which may be 40 adjusted angularly in the radial slots *d*², *d*². (See Fig. 1.)

Upon the bed *a*¹ are arranged bearings *a*², *a*², embodying adjustable conical bushes adapted to grip the mandril or shaft of the copper roller *g*, even though worn; the exterior of the bushes being of cylindrical form 50 and making a running fit in the bearings *a*², *a*², wherewith the roller is consequently maintained true.

The copper roller *g* is driven from the left-hand side of the apparatus illustrated in Fig.

1 by way of a flexible coupling *g*¹, whereof 55 the driving member is keyed upon the driving spindle which carries the three-step cone *g*²; the latter enabling the roller to be driven at three different speeds. More steps may be arranged on the cone *g*² as special requirements may dictate. The driving spindle is carried in a separate casting *g*³, bolted to the left-hand extremity of the bed *a*¹.

The polishing stone *c* and its carrier *c*¹ are hereinafter described and are illustrated more clearly in Figs. 3 and 4. The carrier *c*¹ is driven by means of a reversible driving screw *h*, which engages the driving nut *h*¹. The latter moves along the guide-bars *d*, *d*, which lie between, and are attached to, the 65 brackets *b*, *b*; and to the driving nut *h*¹ is attached a vertical travelling guide-bar *h*². The carrier *c*¹ is free to move up and down upon this latter; but the travelling guide-bar *h*² thrusts the carrier *c*¹ longitudinally 70 from right to left and from left to right. At the top of the travelling guide-bar *h*² is fitted a half-moon-shaped slipper *h*³ which works along the travelling guide-steady-bar *h*⁴, the latter being attached to the brackets 75 *b*.

At the left-hand end of the driving screw *h* is mounted a bevel pinion *h*, which gears alternately with the pinions *h*¹ and *h*², (see Fig. 2) according as they are respectively 85 engaged by the driving clutch *h*³. The latter is keyed upon the driving shaft *h*⁴, whereon the pinions *h*¹ and *h*² are free to revolve until engaged by the clutch *h*³. Toward the outer extremity of the driving 90 shaft *h*⁴, is fixed the main driving pulley *h*⁵.

The clutch *h*³ is operated by means of automatic stops *l*, *l*, carried by a rod *l*; these stops being adjustable as regards their position along the latter in such manner as to 95 suit any given length of copper roller within the range of the machine.

In reversing the traverse of the stone-carrier *c*¹, the mode of operation is as follows:—When the driving screw nut *h*¹ makes contact with either of the automatic stops *l*, *l*, (see Fig. 2) the rod *l* is moved longitudinally, and this motion is transmitted to the reversing lever *l*², which in turn moves the clutch rod *h*⁶, either forwards or rearwardly, and so engages the clutch *h*³ with either the pinion *h*¹ or the pinion *h*². The arms of the reversing lever *l*² may be in the 100 105 110

ratio of 2 to 1 or 3 to 1, so that a very slight movement of the rod l^1 will engage the clutch k^3 fully and almost instantaneously with one of the pinions k^1 or k^2 .

- 5 At the right hand end of the driving screw h , is provided a hand-wheel h^3 for use in rotating the driving screw h when setting the machine at the commencement of its work, or after changing a stone, or for operating the stone-carrier c^1 by hand at any time. This hand-wheel is provided with a friction-nut h^4 , which, when screwed home, locks the hand-wheel in gear; but when the friction-nut is slackened back, the hand-wheel is free and idle, this being the condition required when the driving screw h is being rotated by power.

A counterweight f is employed to counteract the weight of the stone c , its carrier c^1 , and the guide-bars d, d . The guide-bar frame d^1 , when being adjusted, may easily be set at any angle to suit any given width of stone, and there is no danger of the mechanism falling to the bottom of the radial slots in the frames b, b .

As illustrated in Figs. 3 and 4, the stone-carrier c^1 comprises a main casting, at one extremity of which is formed an elongated boss c^2 , through which passes the travelling guide h^2 ; the boss c^2 being made sufficiently long to ensure steadiness. The central portion of the casting is cylindrical and carries a freely revolving ring c^3 . Between the flanges of this ring the guide-bars d, d , bear, and thus a very easy motion is obtained, as the ring is free to revolve both round the main casting and along the guide-bars d, d . The other end of the casting is in the form of a square flange to which is bolted a cover-plate c^4 adapted to retain in position a worm-wheel m . This wheel is internally screw-threaded and engages with a screw-thread formed upon the sliding sleeve m^1 , to which is attached a chuck or grip n adapted to hold the stone c . The chuck n has two jaws operated by a right and left hand screw-threaded spindle p . The back of the chuck is formed with a stem n^1 , which is free to revolve inside the sleeve m^1 and also to partake of a limited longitudinal movement therein. Between the end of the stem n^1 and a plug r , arranged in the upper part of the sleeve m^1 , is placed a spring s . The worm-wheel m is rotated by means of a worm-wheel shaft t operated by means of a hand-wheel v .

The action of the stone-carrier is as follows:—As the latter traverses the roller along the guide-bars d, d , the revolving ring c^3 rotates on the body of the carrier, and the stone c may be advanced or retracted by rotating the hand-wheel v . The latter is attached to the worm-shaft t which drives the worm-wheel m , which in turn advances or retracts the sleeve m^1 , according to the direc-

tion in which the hand-wheel is rotated. The clearance space between the sleeve m^1 and the chuck n is designed to permit the required compression of the spring s .

When the hand-wheel v is rotated until the stone c is brought into contact with the copper roller, a few extra turns are given with the effect that the clearance space is decreased and the spring s is compressed in a certain degree. Such compression ensures an even pressure being exerted by the stone upon the roller throughout its work, and also provides for the taking up of any wear of the stone.

The copper roller having been placed in position and the stone gripped in the carrier, the guide-bar-frame is then set according to the various widths of stones used. The stone is then moved along to the extreme left-hand end of the roller; and in that position, the bottom edge of the stone should lie in exactly the same horizontal plane as the axis of the roller. A few turns of the hand-wheel on the carrier will establish the desired pressure of the stone against the roller. When the stone arrives at the right-hand end of the roller, the top edge of the stone should lie in exactly the same horizontal plane as the axis of the roller. Thus, in each traverse movement of the stone from right to left, or from left to right, along the roller, the stone also moves vertically, the whole surface of the stone is uniformly exposed to the same pressure and the wear evenly distributed. The contact of the stone with the roller is only a line contact at any time, and thus the risk of grit becoming attached to either the roller or the face of the stone is practically obviated.

A water service may be arranged to play upon the face of the stone and roller; the bed a^1 forming a tank or container for the water. Splash guards (not shown) may moreover be attached to the bed a^1 or form part of the casting of the bed.

According to the construction illustrated in Fig. 8, the main body of the stone-carrier c^1 is free to rotate in relation to its rearward portion traversed by the vertical guide-bar h^2 and is formed with peripheral chases c^2 adapted to engage intermittent ribs or teeth c^5 mounted upon the guide-bars d as indicated in dotted line in Fig. 1, the chases c^2 alternately engaging with the ribs or teeth c^5 carried by the respective guide-bars d, d . A reciprocating partial rotary movement of the stone is thus effected as the latter passes to and fro along the guide-bars d . The employment of the additional mechanism here referred to is however optional, as we do not regard it as essential that the polishing stone should partake of any such oscillatory movement as is here provided for.

We claim:—

1. In a machine for polishing copper roll.

- ers, the combination, with guide-bars arranged in a vertical plane parallel with the axis of the roller but in a direction oblique thereto and a stone-carrier mounted in said 5 guide-bars, of frames to which the opposite extremities of said guide-bars are attached, and said frames comprising fixed slotted guides wherein said extremities of said guide-bars are adjustably mounted.
- 10 2. In a machine for polishing copper rollers, a bi-part stone carrier, one part adapted to engage the stone and rotatably mounted in the other part, said first part having peripheral chases, means for moving the stone 15 carrier longitudinally of the roller, said other part having guide bars supporting the stone carrier and having spaced teeth to engage said chases to impart an oscillatory
- movement to the stone carrier during its longitudinal travel.
3. In a machine for polishing copper rollers, means for rotatably supporting a roller, a stone carrier, a pair of guides for said stone carrier, means for supporting the guides at various angles across the horizontal plane 25 of the axis of the roller for shifting the stone carrier vertically when the latter is moved lengthwise of the guides, a device for shifting the stone carrier longitudinally, having a vertically slidable connection between said device and the stone carrier for permitting vertical movement of the stone carrier.
